HINGE MOUNTING FOR CABINET DOORS

Filed Oct. 15, 1926

FIG. 1

FIG. 2

FIG. 3

Inventor
William H. Packer

By W. J. McDowell.

Attorney

UNITED STATES PATENT OFFICE.

WILLIAM H. PACKER, OF COLUMBUS, OHIO, ASSIGNOR TO OHIO STATE STOVE MFG. CO.,
OF COLUMBUS, OHIO, A CORPORATION OF OHIO.

HINGE MOUNTING FOR CABINET DOORS.

Application filed October 15, 1926. Serial No. 141,723.

The invention relates to improvements in hinge mountings for cabinet doors, and has for its principal object the provision of a hinge mounting of simple, improved and economical construction by which an associated door structure may be quickly and properly mounted for swinging movement in connection with the opening of the door frame provided in a cabinet or other similar body.

10 It is another object in the invention to provide a hinge which will be completely concealed from view when mounted in a cabinet and, moreover, one which may be operatively mounted in an economical and labor saving manner.

With these and other objects in view the invention consists in the improved door hinge hereinafter specifically described and pointed out in the appended claims.

20 In the accompanying drawings:

Figure 1 is a vertical sectional view taken thru a cabinet provided with the door hinge comprising the present invention.

25 Figure 2 is a vertical transverse sectional view taken on line 2—2 of Figure 1.

Figure 3 is a perspective view of lower member of the door hinge.

Referring more particularly to the drawing the numeral 1 designates a sheet metal 30 casing of the kind employed, for example, in the construction of wall or medicine cabinets, said casing being formed to include the usual side walls 2, a back wall 3, and top and bottom walls 4 and 5 respectively. The front 35 wall 6 of the casing is formed with the usual opening 7 for the reception of a swinging door 8, by which access to the interior of the casing is afforded. It will be understood that the interior of said casing may be provided with shelves, partitions, and the like, in accordance with the purpose of such articles.

To effect the swinging mounting of the door, the latter in this instance, is in upper right hand corner thereof provided with a fixed stud or pintle 9, which is received within an opening provided in an inturned flange 10 formed on the wall 6 along the upper edge of the opening 7. The lower right 45 hand corner of the door is hingedly mounted by the provision of a wire member 11. This member, as shown in Figure 1, is formed to include a longitudinally extending arm 12, which is located immediately below the bottom wall 5 of the casing, said arm termini-

nating at one end in a looped or bent portion 13, which, in turn, terminates in an arm 14, extending downwardly and at an acute angle to the arm 12. The lower part of the arm 14 terminates in a laterally bent portion 15 60 which engages with a flange 16, formed on the lower horizontal edge of the wall 6.

By this construction the member 11 is resiliently confined under tension between the flange 16 and the bottom wall 5, and this 65 tension is sufficient normally to hold the wire member in its operative position occupying a substantial vertical plane immediately behind the wall 6. If desired, however, the extremity 15 of the member may be welded 70 to the casing so as to insure the permanent retention of said wire member in the casing. The outer end of the longitudinally extending portion 12 of said wire member is bent to produce a vertical pintle 17 which is disposed 75 in vertical alignment or registration with the pintle 9 at the upper end of the door, the said pintle 17 passing thru an opening 18 provided in the bottom wall 5 and into a receiving socket 19 provided in lower right 80 hand corner of the door.

It will be seen that by the provision of the construction described, a simple, effective and efficient pivoted mounting is provided for effecting the swing mounting of the door 85 in such manner that the pivot construction will be entirely concealed from external view. This is highly essential in wall cabinets, where smooth flat lines are desired, devoid of the breaks which are produced by the employment of hinge means of ordinary form. Not only does the concealed hinge produce an improved appearance, but it, also, assists in keeping the casing in cleanly condition, since the concealed hinge does not interfere with 90 the free operation of a cleaning cloth.

Another feature of outstanding importance from a manufacturing standpoint is the extreme simplicity of the construction and ease and quickness with which the structure 100 can be assembled. Tests have disclosed that the door can be mounted in but one third of the time, which, heretofore, has been required in assembling previous types of structures. If desired, the door can be readily demounted 105 by resiliently drawing the portions 12 and 14 of the wire member together, which will withdraw the pintle 17 from the socket 19 and allow the door to be thereby removed.

It is, of course, understood that the in- 110

vention is not limited to the precise details of construction and arrangement as herein set forth, as it is obvious that various modifications may be made therein without departing from the essential features therein as defined in the appended claims.

What is claimed is:

1. In a cabinet of the character set forth, a casing structure having an opening in the front wall thereof, a door arranged in said opening, pivot means for supporting said door consisting of a fixed pintle and socket construction for one corner of said door, and a wire member for supporting the other corner of said door, said wire member being formed to include a pair of angularly disposed arms arranged within said casing structure and resiliently movable with respect to each other, one of said arms being provided at its outer end with a pintle arranged in registration with said first named pintle and removably positioned within a socket provided in one corner of said door.
2. In a cabinet, a casing formed to include a horizontal and a front wall, said front wall being provided with an opening, a door arranged to occupy said opening, said front wall being provided along one of the edges thereof with an inturned flange, a pivotal mounting for said door comprising a wire member bent medially to produce resiliently separable arms, said arm portion being confined within said casing between said horizontal wall and said flanges, one of said arms

being formed to comprise a pintle arranged to pass through an opening in said horizontal wall and to be received within a socket provided in the adjacent part of the door, and an angular bent portion formed with the other of said arms and arranged to rest upon the said flange.

3. In a cabinet, a casing having a door opening formed therein, a door arranged to occupy said opening, a pivotal mounting for said door comprising a wire member bent medially to produce resiliently separable arms, said arms being confined under tension within said casing, and a pintle formed upon one end of one of said arms and receivable within a socket provided in said door.

4. In a cabinet, a casing formed to include a horizontal and a front wall, said front wall being provided with an opening, a door arranged to occupy said opening, said front wall being provided along one of the edges thereof with an inturned flange, a pivotal mounting for said door comprising a wire member bent medially to provide spaced arm portions, said arm portions being confined within said casing between said horizontal wall and the flange of said front wall, and one of said arms being formed to comprise an angularly bent pintle arranged to pass thru an opening in said bottom wall and to be received within a socket provided in the adjacent part of said door.

In testimony whereof I affix my signature.
WILLIAM H. PACKER.
